UNITED STATES PATENT OFFICE

98,232

DESIGN FOR A GAME BOARD

Tsai C. Chi, Chicago, Ill.

Application November 27, 1935, Serial No. 59,803

Term of patent 7 years

To all whom it may concern:

Be it known that I, Tsai C. Chi, a citizen of the Republic of China, residing at Chicago, in the county of Cook and State of Illinois, have invented a new, original, and ornamental Design for a Game Board, of which the following is a specification, reference being had to the accompanying drawing, forming part thereof, and in which:

Fig. 1 is a plan view of a game board showing my new design; and

Fig. 2 is an end view.

I claim:

The ornamental design for a game board, as shown.

TSAI C. CHI.
